UNITED STATES PATENT OFFICE

HERMANN HOFFMEISTER, OF GLIESMARODE NEAR BRUNSWICK, GERMANY, ASSIGNOR TO BRUNSVIGA-MASCHINENWERKE GRIMME, NATALIS & CO., AKTIENGESELLSCHAFT, BRAUNSCHWEIG, GERMANY, OF BRUNSWICK, GERMANY, A CORPORATION OF GERMANY

CALCULATING MACHINE

Application filed July 23, 1927, Serial No. 208,012, and in Germany May 8, 1927.

My invention relates to improvements in calculating machines of the type in which the numeral wheels are subdivided in several groups disposed in axial alignment one beside the other, the said groups of numeral wheels either forming parts of the same registering mechanism or providing independent registering mechanisms. In machines of this class resetting mechanism has been provided by means of which all the numeral wheels can be simultaneously reset, or each or a plurality of groups of numeral wheels can be reset independently of other groups. Mechanism of this type has been shown for example in the patent to Stemmler and Schaller, No. 1,061,137, of May 6, 1913. The object of the improvements is to provide a calculating machine of this type in which a single resetting shaft is provided for resetting all the groups of numeral wheels or some of the groups of numeral wheels, and with this object in view my invention consists in providing the said resetting shaft with a plurality of keys one for each group of numeral wheels and provided with fingers for resetting the numeral wheels and adapted to be separately shifted with the said fingers into position for engaging the numeral wheels.

For the purpose of explaining the invention an example embodying the same has been shown in the accompanying drawings, in which the same letters of reference have been used in all the views to indicate corresponding parts. In said drawings,

Fig. 1 is a sectional elevation showing a registering mechanism comprising two groups of numeral wheels, one numeral wheel being illustrated in each group,

Fig. 2 is a sectional elevation taken on the line 2—2 of Fig. 1 and looking in the direction of the arrows,

Fig. 3 is a top plan view of Fig. 1, and

Fig. 4, a view similar to Fig. 1, showing a modification.

In the example shown in the figures the registering mechanism of the calculating machine is disposed in a casing comprising a bottom plate 81 and side walls 8, 8¹, the said side walls being provided with recesses 19 and 19¹. In the said recesses annular disks

4 and 4¹ are mounted which provide bearings for a resetting shaft 1 having a crank 2 fixed thereto. On the said resetting shaft two groups of numeral wheels 15 and 15¹ are mounted in a manner known in the art. The resetting shaft 1 is provided with a longitudinal groove having two slidable keys 3 and 3¹ shiftable therein, which keys are provided with fingers 20 and 20¹ adapted for engagement with pins 21 and 21¹ of the numeral wheels 15 and 15¹, the said fingers 20, 20¹ and pins 21, 21¹ being adapted to transmit resetting movement from the shaft to the numeral wheels 15 and 15¹. Normally the fingers 20 and 20¹ are out of position for engagement with the pins 21, 21¹, and they are adapted to be thrown into position for engagement therewith by shifting the keys 3 and 3¹ in axial direction. The keys 3 and 3¹ are formed with noses 16 and 16¹ acted upon by coiled springs 11 and 11¹ tending to shift the keys with the fingers 20 and 20¹ respectively into and out of position for engagement with the pins 21 and 21¹. The hubs of the disks 4 and 4¹ are formed with cam faces 5 and 5¹ adapted for engagement with pins 17 and 17¹ fixed to the keys 3 and 3¹, the said cams controlling the movement of the keys 3 and 3¹ relatively to the pins 21 and 21¹. As shown the cam 5 is in the form of a lug projecting inwardly from the hub of the disk 4, and the cam 5¹ is in the form of a recess made in the hub of the disk 4¹. Thus, when rotating the resetting shaft relatively to the disk 4, as will be described hereinafter, the pin 17 gets out of engagement with the cam 5 so that the spring 11 shifts the bar 3 to the right to move the fingers 20 into position for engagement with the pins 21, until at the end of the rotary movement of the shaft 1 the pin 17 slides again on the cam 5 thus shifting the fingers 20 out of operative positions. In a similar way, when turning the shaft 1 relatively to the disk 4¹ the pin 17¹ slides on the cam 5¹ for throwing the fingers 20¹ into position for engagement with the pins 21¹, and at the end of the rotary movement of the shaft 1 the spring 11¹ shifts the key 3¹ to the left to move the fingers 20¹ out of position for engagement with the pins 21¹.

The disks 4 and 4¹ can be separately coupled to the shaft 1 by means of coupling disks 14 and 14¹ fixed to the said shaft. The said coupling disks are formed at their circumferences each with a slot 13 and 13¹ respectively, and the annular disks 4 and 4¹ are formed with similar slots 18 and 18¹ respectively, and in the slots 18 and 18¹ latch bolts 6 and 6¹ are radially shiftable, and are acted upon by springs 7 and 7¹ tending to shift the same outwardly. The bolts 6 and 6¹ are adapted to be forced inwardly against the action of the springs 7 and 7¹ by keys 12 and 12¹, and when being thus forced inwardly the bolts 6 and 6¹ engage the slots 13 and 13¹ thus coupling the disks 4, 14 and 4¹, 14¹ respectively. To the outer faces of the side members 8 and 8¹ of the casing of the registering mechanism rings 10 and 10¹ are fixed, which are formed at their inner circumferences each with a slot 9 and 9¹, the slots 9 and 9¹ being located so that the bolts 6 and 6¹ are adapted to pass into the same, as appears from the left hand part of Fig. 1. But after depressing the bolts 6 and 6¹ and turning the shaft 1 the bolts 6 and 6¹ are out of position for engagement with the slots 9 and 9¹ and they are held in depressed positions by the inner circumferences of the rings 10 and 10¹.

When a bolt 6 or 6¹ is in its outward position shown at the left in Fig. 1 it engages the slot 9 or 9¹ thus fixing the annular disk 4 or 4¹ in position relatively to the rings 10 or 10¹ and preventing rotary movement of the disk 4 or 4¹. If now the resetting shaft 1 is turned through an angle of 360° for resetting a group of numeral wheels operable by said shaft the pin 17 or 17¹ is shifted to the right by the cam 5 or 5¹ into position to engage the corresponding numeral wheels, so that the engaged group is reset, the bolt 6¹ engaging the slot 9¹ and fixing the disk 4¹ in position. At the end of the resetting movement of the shaft 1 the key 3¹ and pin 17¹ are returned into the position shown in Fig. 1 by the spring 11¹.

If now a key such as 12 is depressed, the bolt 6 is moved out of the slot 9 and enters the slot 13 of the coupling disk 14. Thus the disk 4 takes part in the rotary movement of the resetting shaft 1, and it does not shift the corresponding key 3 into resetting position. Thus the group of numeral wheels 15 is not reset. While turning the shaft 1 the bolt 6 is held in depressed position by the inner circumference of the ring 10. Thus depression of the keys 12 or 12¹ is necessary only at the beginning of the rotary movement of the resetting shaft.

In Fig. 1 I have shown two groups of numeral wheels forming a part of a single registering mechanism. It will be understood that the said groups may form separate mechanisms. Such a modification is illus-

trated in Fig. 4, which shows a partition 25 between the said groups of numeral wheels.

While in describing the invention reference has been made to a particular example embodying the same I wish it to be understood that my invention is not limited to the construction shown in the drawings, and that various changes may be made in the general arrangement of the apparatus and the construction of its parts without departing from the invention.

I claim:

1. In a calculating machine, the combination of registering means comprising a plurality of groups of axially aligned registering members, a rotatable resetting shaft common to all of said groups said shaft having a continuous groove resetting means for each of said groups, including elements arranged in said groove in operative relation to the individual groups and means whereby said elements can be connected to all the groups of registering members to reset them all simultaneously or to any desired group for resetting its members independently of other groups.

2. In a calculating machine, the combination of registering means comprising a plurality of groups of axially aligned registering members, a rotatable resetting shaft common to all of said groups said shaft having a continuous groove, and separate resetting means for each of said groups, including a separate key in said groove for each of said groups, and means for selectively connecting the keys to the registering members in the operation of the resetting shaft to reset such groups either simultaneously or independently.

3. In a calculating machine, the combination of registering means comprising a plurality of groups of axially aligned registering members, a rotatable resetting shaft extending axially of all of said groups, means for holding said shaft against endwise movement at all times, and mechanism for selectively connecting the shaft to any one or all of the registering members for resetting the same on rotation of the shaft.

4. In a calculating machine, the combination of registering means comprising a plurality of groups of axially aligned registering members, a rotatable resetting shaft supporting all of said groups, means for holding said shaft against endwise movement, spaced disks on the shaft having cams on adjacent faces, means for selectively connecting the disks to the shaft to rotate therewith, and means operated by said cams for resetting said registering members.

5. A device as in claim 4, combined with means for holding a non-selected cam against rotation.

6. In a calculating machine, the combination of registering means comprising groups of spaced axially aligned numeral wheels, a ro-

tatable resetting shaft supporting all of said groups, means for holding said shaft against endwise movement, keys slideable on said shaft for engaging the numeral wheels to cause them to rotate with the resetting shaft, and means for selectively connecting the shaft to all or less than all of said groups.

5. A device as in claim 6, said keys being arranged in a common groove extending 10 lengthwise of the resetting shaft.

6. In a calculating machine, the combination of registering means comprising a plurality of groups of axially alined numeral wheels, a rotatable resetting shaft extending 15 axially through all of said wheels and forming a support therfor, means for holding said shaft against longitudinal movement at all times, means for operating the resetting means including a cam disk on said shaft for 20 each group, means normally holding each disk against rotation to cause resetting of the corresponding registering member on rotation of the shaft, and manual means for releasing said holding means selectively where- 25 by either all of said groups may be reset at once or the groups may be reset independ- ently.

7. In a calculating machine, the combination of a casing, registering means in the casing comprising a plurality of groups of axially alined registering members, a rotatable resetting shaft extending across the casing and common to all of said groups, means for holding said shaft against endwise move- 35 ment, a plurality of keys in a longitudinal groove in said shaft; disks on the shaft adjacent opposite walls of the casing said disks having cams on their respective inner faces for selectively connecting said keys to said 40 registering wheels on rotation of the shaft to cause the wheels to rotate with the shaft, spring-pressed bolts carried by said disks, fixed abutments normally engaged by said bolts to lock the disks against rotation with 45 said shaft, manual means for disengaging said bolts from said abutments, and means to hold the bolts out of locking position until the shaft returns to normal position.

8. In a calculating machine, a plurality 50 of cooperating registering members, a rotatable resetting shaft extending axially through all said members, and devices movable endwise of the shaft but constrained to rotate therewith said devices being adapted 55 to be connected either simultaneously or individually to the registering members for resetting them.

In testimony whereof I affix my signature.
HERMANN HOFFMEISTER.
